UNITED STATES PATENT OFFICE.

AUGUSTA S. JOHNSON, OF BROOKLYN, NEW YORK, ASSIGNOR TO MODEL BRASSIERE CO., INC., OF NEW YORK, N. Y., A CORPORATION OF NEW YORK.

BRASSIÈRE.

Application filed February 21, 1923. Serial No. 620,423.

To all whom it may concern:

Be it known that I, AUGUSTA S. JOHNSON, a subject of the King of Sweden, and resident of the borough of Brooklyn, county 5 of Kings, city and State of New York, have invented certain new and useful Improvements in Brassières, of which the following is a specification.

My invention relates to brassières and has 10 for its object to provide a combination brassière and camisole of novel construction adapted particularly for reducing the diaphragm and accomplishing its purpose by having a semi-detached band of a predetermined shape attached to the inside of the garment. Other more specific objects will 15 appear from the description hereinafter.

In the accompanying drawings which illustrate an example of the invention without defining its limits, Fig. 1 is an inside view of the garment; Fig. 2 is a detail section on the line 2—2 of Fig. 1; and Fig. 3 is a detail section on the line 3—3 of Fig. 1.

As shown in the drawings the garment 25 comprises a body 5 constructed in the form of a camisole and preferably cut in three sections attached to each other by sewing 6. At its outer edges the body 5 is provided with cooperating fastening devices 7 such 30 as hooks and eyes whereby the garment may be secured in place upon the wearer; shoulder straps 8 may be attached to the upper edge of the body 5 as illustrated. This body 5 which constitutes what may be 35 termed the outer garment is extremely deep and in practice may measure as much as fourteen inches and is provided at approximately the waist line with relatively narrow elastic inserts 9 which extend from the outer 40 edges to points indicated as 10 and located at opposite sides of the vertical centre line of the garment in spaced relation so as to leave a central section 11 which is absolutely flat and free from any material elasticity. 45 These elastic inserts 9 may run through binding it being understood that the garment or camisole 5 is somewhat full at the waist line; that portion of the body 5 which is continued below the inserts 9 serves to 50 prevent the camisole 5 from riding up over the corset. What may be termed the inner garment comprises a central section 12 of approximately rectangular form to constitute a pad which has its lower portion secured to the body 5 by stitching 13 the upper

edge and the remainder of the section 12 being disconnected and free from the body 5 as shown in Fig. 2. In the preferred construction the central section is provided with a plurality of bones 14 arranged in cross relation as shown in Fig. 1, said bones being secured in place as indicated for instance in Fig. 2 of the drawings. At opposite sides the section 12 is provided with integral continuations in the form of flaps 15 which are 60 detached from the body 5 and are connected therewith only through the medium of the section 12. Elastic bands 16 of rubber or other suitable material are attached to the free ends of the flaps 15 and outer edges 70 of the body 5 as indicated at 17; said elastic bands 16 as shown in Fig. 1 being located in registry with the elastic inserts 9. With the described arrangement the inner garment is partially independent of the 75 outer garment and is attached thereto only at 13 and at 17 as illustrated in Fig. 1; thus when the garment is worn the section 12 is firmly fitted over the diaphragm by the action of the elastic bands 16 and thereby 80 serves all the purposes of an efficient brassière while the outer garment may be made fancy enough and fitted in the manner of a camisole so that it may be worn under a light waist in the customary manner. The 85 invention thus provides an efficient two in one garment constituting a combination fancy camisole and diaphragm reducing brassière which accomplishes its purpose in an efficient manner through the medium of the semi-detached, peculiar shaped band consisting of the pad 12, flaps 15 and elastic bands 16 which are attached to the inside of the garment. If desired hanger slides 18 may be located both at the back and the 90 front for attachment in the usual manner, to prevent any possible slipping of the garment. The garment is extremely simple in construction and may be produced in any ornamental or existing style desired. 95

The improved two in one garment may further be secured upon the wearer by a single operation, it being simply necessary to connect the hooks and eyes 17 to fasten the two garments in place.

In some cases instead of being made of a plurality of sections the camisole or outer garment may be made in one piece, in which case the under arm or side seams 6 would be omitted. The shape of the top and bot-

tom edges of the central section 12 and flaps 15 may be otherwise than as shown; it will further be obvious that the crossed arrangement of the bones 14 need not be exactly as illustrated and that said bones 14 may cross each other in other ways if desired.

Various changes in the specific form shown and described may be made within the scope of the claims without departing 10 from the spirit of the invention.

I claim:

1. A garment comprising a body, a diaphragm reducing pad on the inside of said body at the front thereof and having its 15 lower portion attached thereto and being otherwise free from said body, flaps extending from opposite sides of said section and elastic bands extending from said flaps to the outer edges of said body and attached 20 thereto, said flaps and bands being otherwise free from said body.

2. A garment comprising a body, elastic inserts in said body at approximately the 25 waist line thereof, said inserts extending from the outer edges of the body to points at opposite sides of the vertical centre line thereof, a diaphragm reducing pad on the

inside of said body having its lower portion attached thereto and being otherwise detached from said body, flaps extending from 30 said body in opposite directions, elastic bands located in registry with said elastic inserts and having one end connected with said flaps and the other end attached to said body at the outer edges thereof, said flaps and elastic bands being otherwise free from 35 said body and means for detachably connecting the outer edges of said body.

3. A garment comprising a body, a diaphragm reducing pad on the inside and at 40 the front thereof and having its lower end connected with said body and being otherwise free therefrom, a plurality of bones in said pad arranged in spaced relation to each other, elastic means connected with said pad 45 on its opposite edges and with said body on the outer edges thereof and being otherwise free from said body and means for detachably connecting the outer edges of said body.

In testimony whereof I have hereby signed this specification.

AUGUSTA S. JOHNSON.
